IRON REST

Elmer C. Binggely, Canton, Ohio, assignor to The Hoover Company, North Canton, Ohio, a corporation of Ohio

Application September 22, 1948, Serial No. 50,480

3 Claims. (Cl. 38—79)

1

The present invention relates to improvements in sad irons and more particularly to a new and improved collapsible rest for supporting the sole plate off an ironing surface when the iron is not in use.

A principal feature of the invention is the provision of a collapsible rest for a sad iron which automatically extends upon elevation of the sole plate from an ironing surface.

Another important feature is the provision of a rest which automatically collapses when the iron is pushed away from its rest position.

A further feature is a collapsible rest which is normally housed within the confines of the iron proper and retained there until released by tilting of the iron in a particular manner operable to effectuate the release of the rest.

Other important features of the invention include simplicity of parts and of operation, positive action, low cost, ease of assembly and service and unusual simplicity of use. Still further advantages will become apparent from a consideration of the specification and drawings wherein:

Figure 1 is a side view, partially in section, of an iron incorporating the invention and with the rest extended;

Figure 2 is a view similar to Figure 1 of a modified embodiment of the invention; and

Figure 3 is a fragmentary view of the modified form showing the position of parts of the rest as it is collapsing from its extended position.

Referring first to Figure 1, it will be observed that the invention is shown as incorporated in a conventional electric iron having a sole plate 10, a cover shell 11 and an operating handle 12. These elements may be of conventional form. The sole plate is preferably of the type having an imbedded electric heating element and a thermostatic control device having an adjustable control knob 13 therefor.

It will be observed that the cover shell projects rearwardly of the heel of the iron and that its under side has a closure member 14 which is so shaped and positioned relative to the heel of the iron as to act as a wrinkle eliminator during rearward movement of the iron over material being ironed.

Referring now to the rest, it will be seen to comprise but two simple elements each of which is separately pivoted. These consist of a relatively long control lever 15 pivoted to an upturned portion of the wrinkle eliminator as by rivet 16. Lever 15 extends forwardly within shell 11 and its foremost end 17 is turned to one side to con-

2

trol the position of the iron rest 18 pivoted to the sole plate at 19. A torsion spring 20 positioned about pin 16 urges lever 15 counterclockwise into engagement with the shorter end of rest 18 forwardly of its pivot.

Rest 18 comprises a relatively short lever mounted for pivotal movement in a slot 21 formed in the central portion of the sole plate. The longer end of the rest is serrated or roughened and rounded on its forward corner for a purpose which will become apparent later. The shorter end is shaped to abut a portion 27 of the sole plate when the rest is in retracted position which is somewhat above the lower surface of the sole plate as indicated in Figure 1. It will also be clear that abutment 27 acts as a stop for the rest when the latter is in its extended, iron supporting position.

In order that control lever 15 may be moved clockwise by the user so as to permit extension of the gravity actuated rest lever 18, lever 15 is provided with a release button 23 projecting through an opening 24 in the bottom of wrinkle eliminator 14. This button is so designed as to

project from the lower surface of the wrinkle eliminator only a short distance when the rest is in retracted position. Due to the location of the button in proximity to pivot 16 it will be obvious that only a slight upward movement of the button is required in order to release the rest. The control lever and the wrinkle eliminator associated therewith are held in place on the underside of the cover shell by means of a bracket 25 and a single screw 26. Removal of screw 26 permits withdrawal of the wrinkle eliminator together with control lever 15 and button 23.

In operation, the rest is held collapsed, as indicated in dotted lines in Figure 1, by means of torsion spring 20. In these circumstances, tab 17 on the forward end of the control lever rests on the shorter top side of rest 18 and holds it retracted against abutment 27 of the sole plate. Should the user wish to support the iron with the sole plate out of contact with the material being ironed, she merely tilts the iron backward upon the rear edge of the wrinkle eliminator. In so doing, button 23 contacts the ironing surface and rotates the control lever upward permitting rest 18 to fall by gravity. Slight backward movement of the iron with rest 18 in contact with the ironing surface brings the center line of the rest slightly forward of vertical line 28 passing through pin 19. The iron is now supported in a stable rest position upon the rear-most corner of the wrinkle eliminator and the

3

bottom of rest 18. In this position the sole plate is completely above the surface of the ironing board and may be safely left without danger of burning the board or any material beneath the iron proper.

To collapse the rest and return the iron to ironing position, it is merely necessary for the operator to grasp the handle and push the iron forward slightly. In this operation the serrated lower end 22 of the rest digs into the material and pivots the rest counterclockwise into its collapsed position as the sole plate comes back to rest upon the ironing board. At the same time the control lever 15 is urged counterclockwise by spring 20 so as to retract rest 18 entirely within the confines of the lower edge of slot 21. The operator may then continue to iron, lifting the iron at will without danger of the rest extending itself or assuming a position in which parts thereof would catch in the material being ironed.

The second embodiment shown in Figures 2 and 3 operates similarly. The same or similar parts are indicated by the same numerals primed and will not be redescribed here.

As in the first embodiment, the rest comprises two pivoted levers, namely, a control lever 30 and a rest lever or sector 31. Control lever 30 is pivoted to the sole plate intermediate its end by a pin 32 and is urged clockwise by a torsion spring 33. The rearmost end of the control lever projects a slight distance through an opening 34 formed in wrinkle eliminator 35. This end is turned over to form a relatively wide area button 36. The forward end of the control lever has an upturned nose 37 offset from the main body of the lever. It comprises a forward locking surface 38 and a rearward cammed surface 39 whose function will become apparent below.

Rest sector 31 is pivoted at its forward end to the sole plate by a pin 40 positioned at the forward end of a slot 41 formed in the central mid-portion of the sole plate. The rearmost corner of the sector has an upturned tab 42 located in the path of nose 37 on control lever 30. The forward corner of the sector is preferably serrated at 43 to facilitate proper operation of the rest and in particular counterclockwise rotation of the sector when collapsing it to its retracted position.

In operation, assuming the iron supported on an ironing surface, the iron can be placed in a rest position by the operator tilting it backwards onto the rear corner of the wrinkle eliminator 35. In so doing, button 36 of the control lever strikes the ironing surface and is rotated counterclockwise so that nose 37 moves out of the path of tab 42 on rest sector 31. This sector then rotates downwardly by gravity into engagement with the ironing surface where it cooperates with the rear-most portion of the wrinkle eliminator or of the shell to support the sole plate entirely above the ironing surface. In so doing, the forward upper corner of the sector engages the end of slot 41 in the sole plate which acts as a sector stop.

Return of the iron to its normal operating position will be best understood by reference to Figure 3. As in the preferred embodiment, return of the iron is accomplished by tilting the iron forwardly on the rest sector. As the sector rotates counterclockwise the upper inner corner of tab 42 engages cam surface 39 of control lever 30. Continued upward movement of the sector rotates lever 30 counterclockwise against the action of spring 33. As tab 42 over-rides nose 37 the spring will rotate the control lever clockwise a short dis-

4

tance and surface 38 will act on tab 42 to lift the lower edge of the sector slightly above the bottom surface of the sole plate and firmly hold it in this position until the iron is again tilted backwardly to operate button 36.

From the foregoing description of two specific embodiments of the invention it will be readily appreciated that numerous other designs and arrangements of parts can be made without departing from the spirit of this invention or the basic principles thereof.

I claim:

1. An electric sad iron comprising, a sole plate, a cover shell therefor, an operating handle overlying and connected to said shell, a retractable rest for supporting said iron in an inclined position with said sole plate out of contact with an ironing surface comprising two movable members one of which serves as an iron supporting rest and the other as a control member for holding said rest normally in the retracted position thereof, said sole plate having an elongated slot extending lengthwise thereof near the forward end of said sole plate, means near the forward end of said rest member pivotally supporting the same in said slot for movement between a retracted position above the surface of said sole plate and an extended iron supporting position therebelow, said control member being pivotally supported within said cover shell and having a forward end positioned to engage said rest when the latter is in retracted position to hold the rest retracted, the rear end of said control member projecting downwardly at the rear of said sole plate and having an exposed end terminating slightly above the surface of said sole plate, said control member being movable to a position out of contact with said supporting rest when the forward end of the iron is tilted backwardly on the rear end thereof until the exposed end of the control member is moved upwardly by contact with the ironing surface thereby releasing said rest for movement by gravity action to its extended iron supporting position, means for biasing said control member into contact with said rest to hold the same in its retracted position, said control and rest members having cammed inter-engaging surfaces shaped to permit said rest to pivot upwardly past the forward end of said control member when returning to the retracted position thereof and to be re-engaged and held in said retracted position by said control member.
2. The combination with an electric iron of the type having a sole plate, a cover shell overlying the sole plate and extending rearwardly beyond the heel of the sole plate and an operating handle; of a supporting structure for supporting the iron in cooperation with the extended end of the cover shell with the sole plate elevated above a supporting surface comprising, an elongated rest member having a mounting end and a supporting end, said sole plate being formed with a slot adapted to receive said rest member, a pivot on said sole plate above the ironing surface thereof pivotally mounting said rest member on said sole plate for movement in a vertical plane between a retracted position in which said rest member lies within said slot and a supporting position in which one end of said rest member projects from said slot below the ironing surface of the sole plate, said pivot engaging said rest member adjacent the other end thereof whereby the center of gravity of the rest member lies between said pivot and said one end thereof and said one end

of the rest member is biased by gravity to said iron supporting position; and a latching and releasing structure for said rest member comprising, a control lever, means mounting said control lever on the iron for movement between a first position in which a portion of said control lever directly engages said rest member in the retracted position thereof and retains said rest member in such position and a second position in which said portion of said control lever disengages from said rest member to allow said rest member to move by gravity to said supporting position, means normally biasing said control lever to said first position, and means for moving said control lever to said second position including an actuating button engaging said lever and projecting downwardly rearwardly of the heel of the sole plate and terminating slightly above said ironing surface in position to engage a supporting surface and actuate said control member when the iron is tilted backwardly onto said end of the cover shell.

3. The combination with an electric sad iron of the type having a sole plate, a cover shell and an operating handle; of a retractable structure for supporting the iron with the sole plate elevated above a supporting surface comprising an elongated rest member, said sole plate being formed with an elongated slot opening through the ironing surface thereof and adapted to receive said rest member, a pivot on said sole plate above the ironing surface thereof pivotally mounting said rest member in said slot for vertical movement about a horizontal axis to move from a retracted position in said slot to a supporting position in which one end of the rest projects below the ironing surface, said pivot engaging the rest member

adjacent the other end thereof whereby the center of gravity of the rest member lies between the pivot and said one end thereof and the rest member is biased by gravity to iron supporting position; and means for securing said rest member in said retracted position and for releasing said rest member to move to said supporting position by gravity comprising a control and securing lever having a securing portion adapted to engage said rest and an actuating portion extending downwardly at the rear of the heel of said sole plate, means pivotally mounting said control lever on said iron for arcuate movement between a first position in which the actuating portion thereof terminates just above the plane of the ironing surface and the securing portion thereof directly engages the rest in said retracted position and retains the rest in said retracted position and a second position in which said actuating portion moves upwardly with respect to the sole plate and said securing portion disengages from said rest, and means normally biasing said control lever to said first position whereby said rest is released by tilting said iron backwardly to engage said actuating portion with a supporting surface.
